UNITED STATES PATENT OFFICE.

LINCOLN MANNING, OF CLARKSVILLE, CALIFORNIA.

BEVEL-GAGE.

SPECIFICATION forming part of Letters Patent No. 596,413, dated December 28, 1897.

Application filed May 6, 1897. Serial No. 635,332. (No model.)

To all whom it may concern:

Be it known that I, LINCOLN MANNING, a citizen of the United States, residing at Clarks-ville, in the county of El Dorado and State of California, have invented certain new and useful Improvements in Bevel-Gages; and I do declare the following to be a full, clear, and exact description of the invention, such as will enable others skilled in the art to which it ap-5
p pertains to make and use the same.

My invention relates to improvements in bevel-gages for artisans' use; and the object is to provide a simple and efficient device of this class.

15 To this end the novelty consists in the construction, combination, and arrangement of the same, as will be hereinafter more fully described, and particularly pointed out in the claims.

20 In the accompanying drawings the same reference-characters indicate the same parts of the invention.

Figure 1 is a plan view of my improved bevel-gage. Fig. 2 is a longitudinal section 25 on the line 2 2 of Fig. 1. Fig. 3 is a transverse section on the diagonal line 3 3 of Fig. 1.

1 represents the gage-bar, provided with the lateral parallel alined flanges 2 3.

The bar 1 is provided with a longitudinal 30 slot 4 and an orifice 5.

6 represents an integral clamp-bracket ex-35 tends parallel with the contiguous plane face of the bar 1, and its free end is provided with an orifice 7, alined with the correspond-
ing orifice 5 in the bar.

8 represents a plane square blade, the shorter arm 9 of which extends through a longitudinal slot 10 in the flange 2, and an orifice 11 in said arm is brought into alinement with 40 the corresponding orifices in the bar and bracket to receive a pivot-bolt 12, provided with a milled thumb-nut 13 for adjustably securing said arm in place. The longer arm

14 also extends through a longitudinal guide-slot 15 in the flange 2.

16 represents a clamp - bolt extending through the slot 4 in the bar and through an orifice 17 in the heel of an adjustable clamp 18. This clamp is formed with a transverse shoulder 19 and an encompassing jaw 20, which receives the arm 14, and said clamp is adjustable on said arm and the bolt 16 correspondingly adjustable in the slot 4, at any point of which said arm and clamp may be rigidly secured by means of the milled thumb-nut 21.

Having thus fully described my invention, what I claim as new and useful, and desire to secure by Letters Patent, is—

1. The combination of the bar 1, provided with the integral clamp-bracket 6, and hav-60 ing the alined orifices 5 and 7, with the square blade 8, having its shorter arm 9 provided with an orifice 11, and the pivot-bolt 12 provided with the milled thumb-nut 13 adapted to adjustably secure said arm between said bracket 65 and the bar, substantially as shown and described.

2. The combination with the bar 1, provided with the integral clamp-bracket 6, the longitudinal slot 4 and the flange 2 having the 70 guide-slot 15, of the plane square blade 8, having its shorter arm secured between said bar and integral bracket, by a pivot-bolt 12, and the adjustable clamp 18 formed with the transverse shoulder 19, the jaw 20 engaging 75 the longer arm of said blade and the bolt 16 adjustably secured to said slot 4, and engag-
ing said clamp 18 and provided with the milled thumb-nut 21, substantially as shown and described.

In testimony whereof I hereunto affix my signature in presence of two witnesses.

LINCOLN MANNING.
